(57) **ABSTRACT**

A carrier for one or more straws of an appliance such as a dish washing appliance. The carrier and/or rack may be in fluid communication with one or more spray elements when in a stowed position within a dishwasher tub. The one or more carriers may route fluid from the one or more spray elements to wash an interior and/or an exterior of at least one straw. The carrier may include one or more bridges projecting inwardly towards the one or more straws defining one or more pathways for received fluid. The body of the carrier may include one or more adjustable portions. The carrier may be adjustable to engage one or more straws of varying

(Continued)

lengths/diameters. The carrier may include one or more fixed portions. The carrier may include one or more biasing mechanisms.

FIG.

FIG. 9A

FIG. 9

DISHWASHER WITH COLLET STRAW CARRIER

BACKGROUND

The present embodiments relate to a carrier for one or more straws of a variety of diameters/lengths, with particular embodiments shown for a dishwasher rack of a dish washing appliance.

Typical straws are placed in a vertical position within a silverware basket and/or a dishwasher rack. However, this practice often is inconsistent in cleaning the inside and/or outside of the one or more straws with fluid randomly being used during the wash cycle. Thus, there is a need to improve washing of one or more straws of a variety of lengths/ 10 diameters in a dish washing appliance.

SUMMARY

In some embodiments of the invention, for example, a collet straw carrier for a dish washing appliance may include a fixed portion and/or an adjustable portion defining a receptacle configured to receive an end of a straw. In various embodiments, the carrier may include one or more biasing mechanisms. In some embodiments, the one or more biasing mechanisms urges the adjustable portion relative to the fixed portion to releasably engage an end of a straw within the receptacle.

In various embodiments, the one or more biasing mechanisms urges the adjustable portion radially inward relative to the fixed portion towards an end of a straw in the receptacle. In some embodiments, the carrier may include an axial stop within the receptacle. In various embodiments, the adjustable portion may be configurable between a first position at a first radius and a second position at a second radius larger than the first radius. In some embodiments, the one or more biasing mechanisms may have a larger spring force when the adjustable portion is in the second position than the first position. In various embodiments, the carrier may include a first end and an opposing second end, and the adjustable portion may be on the second end and the fixed portion may be on the first end. In some embodiments, the adjustable portion may be hingedly connected to the fixed portion. In various embodiments, the adjustable portion may include two or more pivoting members hingedly connected to the fixed portion. In some embodiments, the adjustable portion may include a circumferential groove receiving the one or more biasing mechanisms. In various embodiments, the adjustable portion may be slidably connected to the fixed portion. In some embodiments, the fixed portion may include one or more slots slidably receiving one or more sliding members of the adjustable portion. In various embodiments, the one or more sliding members may slide perpendicular to an axis of the receptacle. In some embodiments, the one or more sliding members and/or one or more slots may be elongated and extend for a length along an axis of the receptacle. In various embodiments, the one or more bias mechanisms may extend circumferentially about an axis of the receptacle. In some embodiments, the carrier may include a funnel defining an inlet of the receptacle.

In some embodiments, a dish washing appliance may include a dishwasher tub. In various embodiments, the appliance may include one or more spray elements disposed in the dishwasher tub. In some embodiments, the one or more spray elements may include one or more apertures. In various embodiments, the one or more spray elements may be in fluid communication with a fluid supply to direct fluid

from the fluid supply into the dishwasher tub. In some embodiments, the appliance may include one or more collet straw carriers positioned downstream of the one or more spray elements and/or apertures. In various embodiments, the carrier may include a fixed portion, an adjustable portion, and/or one or more biasing mechanisms. In some embodiments, the fixed portion and/or the adjustable portion may define a receptacle configured to receive an end of a straw. In various embodiments, the one or more biasing mechanisms may urge the adjustable portion relative to the fixed portion to releasably engage an end of a straw within the receptacle.

In various embodiments, the adjustable portion may be slidably connected to or hingedly connected to the fixed portion. In some embodiments, the adjustable portion may be slidably connected to the fixed portion. In various embodiments, the adjustable portion may be hingedly connected to the fixed portion. In some embodiments, the bias mechanism may extend circumferentially about an axis of the receptacle. In various embodiments, the appliance may include a funnel defining an inlet of the receptacle. In some embodiments, the one or more biasing mechanisms may urge the adjustable portion radially inward relative to the fixed portion towards an end of a straw in the receptacle. In various embodiments, the appliance may include an axial stop within the receptacle. In some embodiments, the adjustable portion may be configurable between a first position at a first radius and a second position at a second radius larger than the first radius. In various embodiments, the one or more biasing mechanisms may have a larger spring force when the adjustable portion is in the second position than the first position.

In some embodiments of the invention, for example, a method of releasably engaging one or more straws with a collet straw carrier within a dish washing appliance may include providing at least one collet straw carrier within a dishwasher tub. In various embodiments, the carrier may include one or more fixed portions and one or more adjustable portions, and wherein the one or more adjustable portions may move relative to the one or more fixed portions. In some embodiments, the method may include varying a radial position of the one or more adjustable portions relative to the one or more fixed portions. In various embodiments, the method may include releasably engaging an end of a straw.

In various embodiments, the method may include pivoting the one or more adjustable portions relative to the one or more fixed portions. In some embodiments, the method may include sliding the one or more adjustable portions relative to the one or more fixed portions. In various embodiments, the method may include biasing the one or more adjustable portions relative to the one or more fixed portions.

These and other advantages and features, which characterize the embodiments, are set forth in the claims annexed hereto and form a further part hereof. However, for a better understanding of the embodiments, and of the advantages and objectives attained through its use, reference should be made to the drawings and to the accompanying descriptive matter, in which there are described example embodiments. This summary is merely provided to introduce a selection of concepts that are further described below in the detailed description, and is not intended to identify key or essential features of the claimed subject matter, nor is it intended to be used to limit the scope of the claimed subject matter, nor to define the field of endeavor.

BRIEF DESCRIPTION OF THE DRAWINGS

In the drawings, like reference characters generally refer to the same parts throughout the different views. Also, the

drawings are not necessarily to scale, emphasis instead generally being placed upon illustrating the principles of the invention.

FIG. 1 is a perspective view of one embodiment of an upper/third retractable dishwasher rack illustrating two embodiments of a carrier for at least one straw supported by the stowed rack and in fluid communication with one or more spray elements, with portions of the housing and dishwasher tub removed;

FIG. 2 is a sectional view of one embodiment of a carrier taken along line 2-2 being adjustable for one or more straws having a variety of lengths/diameters, and illustrating a straw being loaded into the carrier, expanding a biasing mechanism, and the pivoting members in a second position;

FIG. 3 is a sectional view of the carrier of FIG. 2 illustrating the straw unloaded from the carrier, the biasing mechanism compressing the pivoting members inwardly, and the pivoting members in a first position, wherein the first position is at a smaller radius than the second position;

FIG. 4 is a perspective view of the carrier of FIG. 2;

FIG. 5 is a sectional view of one embodiment of the carrier of FIG. 2 taken along line 5-5 illustrating a straw loaded into one receptacle of the carrier and another receptacle of the carrier without a straw loaded therein;

FIG. 5A is a sectional view taken along line 5a-5a of FIG. 5;

FIG. 6 is a sectional view of another embodiment of a carrier taken along line 6-6 being adjustable for one or more straws having a variety of lengths/diameters, and illustrating a straw being loaded into the carrier, expanding a biasing mechanism, and the sliding members in a second position;

FIG. 7 is a sectional view of the carrier of FIG. 6 illustrating the straw unloaded from the carrier, the biasing mechanism compressing the sliding members inwardly, and the sliding members in a first position, wherein the first position is at a smaller radius than the second position;

FIG. 8 is a perspective view of the carrier of FIG. 6;

FIG. 9 is a sectional view of one embodiment of the carrier of FIG. 6 taken along line 9-9 illustrating a straw loaded into one receptacle of the carrier and another receptacle of the carrier without a straw loaded therein; and

FIG. 9A is a sectional view taken along line 9a-9a of FIG. 9.

DETAILED DESCRIPTION

Numerous variations and modifications will be apparent to one of ordinary skill in the art, as will become apparent from the description below. Therefore, the invention is not limited to the specific implementations discussed herein.

The embodiments discussed hereinafter will focus on the implementation of the herein-described apparatus and techniques within a front-load residential dish washing machine such as dish washing or dish washing appliance 10, such as the type that may be used in single-family or multi-family dwellings, or in other similar applications. However, it will be appreciated that the herein-described apparatus and techniques may also be used in connection with other types of dish washing machines in some embodiments. For example, the herein-described apparatus and techniques may be used in commercial applications in some embodiments.

Embodiments for a dish washing machine 10 are shown herein for ease of understanding. For example, a front-load dish washing machine that includes a front-mounted door 12 in a cabinet or housing 11 that provides access to a horizontally-oriented dishwasher rack 30 housed within the

cabinet or housing 11 may be used. More specifically, the dishwasher rack 30 may be housed in a dishwasher tub 14. Implementation of the herein-described apparatus and techniques within a variety of appliances would be well within the abilities of one of ordinary skill in the art having the benefit of the instant disclosure, so the invention is not limited to the front-load dish washing implementation discussed further herein. For example, the apparatus and techniques may be used with a dishwasher drawer of a dish washing appliance.

Turning now to the drawings, wherein like numbers denote like parts throughout the several views, FIG. 1 illustrates an example dish washing appliance 10 in which the various technologies and techniques described herein may be implemented. Dish washing appliance 10 is a front-load dish washing machine, and as such may include a front-mounted door 12 defining an opening 13 that provides access to a horizontally-oriented dishwasher tub 14. The tub 14 may be defined by at least a rear wall 15 interconnected by two opposing side walls, bottom wall, and a top wall. The door 12 may be coupled with a cabinet or housing 11 that may house the dishwasher tub 14 in some embodiments. Door 12 is generally hinged along a front or front edge of the housing 11 adjacent the opening 13 and is pivotable between the closed position illustrated in FIG. 1 and an open position (not shown). When door 12 is in the open position, dishes, utensils, pans, straws 1, one or more carriers 20, and/or 120, and other washable items may be inserted into and removed from the one or more dishwasher racks 30 through the opening 13 in the front of cabinet or housing 11. Control over dish washing appliance 10 by a user is generally managed through a control panel (not shown) disposed on a door 12 and implementing a user interface, and it will be appreciated that in different dish washing machine designs, control panel may include various types of input and/or output devices, including various knobs, buttons, lights, switches, textual and/or graphical displays, touch screens, etc. through which a user may configure one or more settings and start and stop the wash cycle or straw washing operation as described herein. For example, the control panel, or portions thereof, may be included with the dishwasher rack, on the interior or exterior of the door, and/or adjacent the rack within the opening of the dish washing machine. For example, in some embodiments, portions of the controls may be accessible when the door is in the open position.

As shown in the figures, the one or more dishwasher racks 30, or portions thereof, may be positionable relative to the dish washing appliance 10 between a stowed or un-deployed position (FIG. 1) and a deployed or different position (not shown). At least one of the stowed positions of the dishwasher rack 30 may be used when one or more of the washing or straw washing cycles is in operation. In use, the deployed position may be one or more horizontal positions different from one or more of the stowed positions. For example, one deployed position or partially opened position may be a position other than when the rack is in its fully extended position out of the dishwasher tub 14. One or more deployed positions may be a horizontal position to dry, load, and/or unload dishes, utensils, one or more straws 1, one or more carrier(s) 20 and/or 120, or the like. The one or more dishwasher racks 30 and/or carrier may travel in a substantially horizontal plane. The horizontal plane may be into and/or out of the dishwasher tub 14 or cavity. Although the substantially linear movement of the dishwasher rack cycle and/or carrier may occur along the horizontal plane in a variety of heights as shown, the linear travel may be in a

variety of angles in one or both the directions into or out of a position. The straw carriers may be moveable between positions and/or fixed in position relative to the dish washing appliance, or portions thereof and still be in at least one position to be in fluid communication with and/or used to receive fluid (e.g. first fluid F1, second fluid F2, etc.) from one or more spray elements 40.

As illustrated in the figures, one or more collet straw carriers or carriers 20, 120 may be used to releasably engage, receive, or temporarily retain one or more straws 1 to be washed within the dishwasher 10 and/or rack 30. The straws 1 may be a variety of shapes, sizes, constructions, and quantities. For example, a variety of outer diameters DD and/or lengths. The one or more carriers 20, 120 may be supported within the rack 30 (e.g. upper or third rack) and deployed with the rack 30 from at least one stowed position (See FIG. 1) to at least one deployed position. Alternatively, the carrier may be positioned in the tub separate from the rack. In the deployed position, one or more straws 1 may be inserted or removed from the carrier 20, 120. In the stowed position, the carrier 20, 120 may be in fluid communication with and/or used to receive fluid (e.g. first fluid F1, second fluid F2, etc.) from one or more spray elements 40 (e.g. docking station 41, spray arm 42, etc.) to wash an interior and/or exterior of the one or more straws 1 positioned/received within the carrier 20, 120. The carrier may fluidly engage or be configured to receive fluid from the one or more spray elements 40 when in a position (e.g. stowed/deployed rack position). A spray collector 27a, if used, may receive fluid from the spray element 40. A pin jet sprayer, if used, may receive fluid from the spray element 40. Although the carrier 20, 120, or portions thereof, (e.g. first end 20a, inlet(s) 22a, spray collector 27a, pin jet sprayer) is shown in FIG. 1 as fluidly engaging and/or sealing against the spray element 40 (e.g. docking station 41) when in the stowed position (e.g. rack 30 and/or carrier), it should be understood that the carrier, or portions thereof, may be spaced (e.g. one or more distances) from the spray element and still be in fluid communication with the water supply/spray element during one or more wash or straw wash cycles.

In some implementations, the carrier 20, 120 and/or receptacle 22 may temporarily receive or releasably engage one or more straws 1 to receive fluid directed from the one or more spray elements 40 and route the received fluid across the one or more surfaces or peripheries of the respective straw 1. The carrier 20, 120 may include a body 21 having a first end 20a and an opposing second end 20b. The carrier 20, 120, fixed portion 28, and/or adjustable portion 26 may define one or more portions of the receptacle 22 extending between the first end 20a and the second end 20b. The first end 20a of the carrier 20, 120, may define one or more inlets 22a of the receptacle 22. The second end 20b of the carrier 20, 120 may define one or more outlets 22b of the receptacle 22. The second end 20b (e.g. fixed portion, adjustable portion) may define a funnel 29. The funnel 29 may define the receiving end or outlet 22b of the receptacle 22. The inlets 22a are in fluid communication with the outlets 22b along the length, or portion thereof, of the body 21. An end 1a or 1b of the straw 1 is positioned in the receptacle 22 between the inlet 22a and the outlet 22b, or downstream of the inlet 22a and upstream of the outlet 22b. The received fluid (e.g. first fluid F1) is directed from the inlet 22a past one end 1a of the straw 1 (e.g. first opening), progressively along the interior 1c and/or exterior 1d periphery of the straw 1, to discharge from the outlet 22b or receptacle 22. In some embodiments, the forced or received fluid is channeled through one or more pathways 25 along

the body 21 or end 1a, 1b, or portions thereof, and the interior and/or exterior periphery 1c, 1d (e.g. portion of straw length) from the inlet 22a towards the outlet 22b of the receptacle 22 or body 21 to wash the straw 1, or portions thereof. A single straw 1 may be positioned in the receptacle 22 or carrier 20, 120. However, more than one straw may be received within the carrier or receptacles. The first end 20a or axial/terminating end of the carrier 20, 120 may define at least one inlet 22a. The inlet 22a may face axially away or upstream from the body 21 (e.g. elongated cylindrical shape) towards the spray element 40, rear wall 15, and/or in the direction of travel of the rack 30. The first end 20a of the body may include a spray collector 27a. In the one embodiment shown, the spray collector 27a, if used, may be a conical shape or funnel tapering towards the remaining portion of the carrier body 21 or second end 20b away from the first end 20a. In some implementations, the carrier 20, 120 and/or appliance 10/rack 30 may include one or more pin jet sprayers. The first end 20a may include the one or more pin jet sprayers. The pin jet sprayer, if used, may be used downstream of one or more docking stations 41 and/or spray collectors 27a, if used, to force received fluid (e.g. F1) through the carrier 20, 120 and/or straw interior/exterior 1c, 1d. The second end 20b or axial/receiving end of the carrier 20, 120 may define the outlet 22b and/or receptacle 22 releasably engaging/receiving the end 1a of the straw 1. The outlet 22b may face axially away or downstream from the body 21 (e.g. elongated cylindrical shape) towards the door 12, opening 13, and/or in the direction of travel of the rack 30. In the one embodiment shown in the Figures, the first end 20a may include a single inlet 22a and the downstream second end may include a plurality of outlets 22b and/or receptacles 22 downstream of one or more pathways connected to the inlet 22a.

In some implementations, the carrier 20, 120, or portions thereof, may be releasably or fixedly supported in one or more racks 30. The carrier 20, 120, or portions thereof, may be releasably attached to the rack. This may allow for different straw carriers 20, 120 to be used in one or more locations within the appliance 10 and/or racks 30. In other embodiments, the carrier 20, 120 may be fixed in position with the rack 30 or appliance. Further, although two carriers 20 and 120 are shown in the Figures within the rack 30, one or more carriers (e.g. same or different shapes, sizes, orientations, and/or positions) may be used in the rack 30 at the same/different times engaging one or more spray elements (e.g. same, different).

One or more carriers may be positioned in a variety of orientations within the rack 30 and still be in fluid communication with one or more spray elements 40. In the one embodiment shown in FIG. 1, the carrier 20, 120, straw 1, receptacle 22, inlets 22a, outlets 22b, and/or pathways 25 are orientated in a substantially horizontal position. The carrier 20, 120 may be positioned adjacent the rear of the rack 30. In some embodiments, the first end 20a and/or inlets 22a may be positioned adjacent the rear of the rack 30 or adjacent the rear wall 15 of the dishwasher tub 14 when in the stowed position. The second end 20b and/or outlets 22b may be positioned towards or adjacent the front of the rack 30 or adjacent the opening 13 of the dishwasher tub 14 when in the stowed position. When the carrier 20, 120 receives fluid from the spray element 40 in the one embodiment shown, at least some water or fluid (e.g. F1) is forced (e.g. horizontally) through the carrier 20, 120 from the inlet 22a towards the outlet 22b (e.g. from the rear wall 15 towards the opening 13 of the tub 14).

In some implementations, the appliance 10 and/or carrier 20, 120 may include one or more spray elements 40 or apertures. The spray element(s) 40 may be in fluid communication with one or more fluid supplies 16 to direct fluid from the fluid supply 16 into the dishwasher tub 14 and/or carrier(s) through the one or more spray elements 40 (e.g. one or more apertures, pathways, devices). One embodiment of the spray element 40 includes one or more docking stations 41 in fluid communication with the one or more carriers 20, 120. As shown in FIG. 1, the docking stations 41, if used, may be adjacent to or in the rear wall 15 of the dishwasher tub 14. The one or more inlets 22a/outlets 22b of the carrier 20, 120 are in downstream fluid communication with the one or more docking stations 41 or spray elements 40 when the rack/carrier is in the stowed position. Further, in some embodiments as shown in FIG. 1, the spray element 40 may include one or more spray arms 42. The spray arms 42, if used, may direct water or fluid into or towards the carrier 20, 120 to wash one or more portions of the straw(s) 1. As shown in the one embodiment in FIG. 1, the spray arm 42 (e.g. positioned above the carrier 20, 120) sprays or directs fluid (e.g. F2) from one or more apertures towards (e.g. downwardly) at least an exterior periphery 1d of the straw 1 and/or interior/exterior of the carrier (e.g. secondary openings and/or spacing/gaps between movable/fixed portions) and/or the docking station 41 sprays or directs fluid (e.g. F1) from one or more apertures towards the interior/exterior of the straw 1 and/or interior of the carrier. Although not shown, it should be understood that the spray arm, in some embodiments, may direct fluid towards the interior of the straw alone or in combination with the exterior of the straw.

In some implementations, the carrier 20, 120, adjustable portion 26 (e.g. member(s) 26a), fixed portion 28, and/or dish washing appliance 10 may include one or more bridges, stands, splines, or offsets 24 to create or define fluid pathways 25, or portions thereof, around the one or more straws 1 (e.g. interior and/or exterior). The adjustable portion 26 and/or fixed portion 28 (e.g. interior wall/periphery/members) may include one or more splines 24, if used. In the one embodiment shown in the FIGS. 2-9A, the one or more splines 24 may include one or more protrusions 24a (e.g. elongated, extend for a length along axis of receptacle) projecting from the interior wall 21e of the carrier interior 21d, member 26a (e.g. sliding, pivoting), and/or adjustable portion 26, or portions thereof. In the one embodiment shown in the FIGS. 2-9A, the one or more splines 24 may include one or more protrusions 24b (e.g. elongated, extend for a length along axis of receptacle) projecting from the interior wall 21e of the carrier interior 21d and/or fixed portion 28, or portions thereof. The one or more protrusions 24a and/or 24b, if used, may space/position the one or more exterior peripheries 1d of the straw(s) from the remaining portion of the interior 21d of the body 21 and/or carrier 20, 120. The remaining portion of the interior 21d (e.g. internal wall) may not include the one or more protrusions or splines. The one or more protrusions 24a, 24b may project inwardly from the interior 21d of the body 21 towards the one or more straws 1, or portions thereof. One or more pathways 25 for received fluid (e.g. F1, F2) may be defined between the remaining portion of the carrier, one or more protrusions 24a, 24b, and/or the interior/exterior periphery 1c, 1d of the one or more straws 1. The one or more protrusions 24a, 24b may taper inwardly towards the straw 1. In some implementations, the one or more protrusions 24a, 24b may be radial protrusions. The one or more protrusions 24a, 24b may project (e.g. radially) from at least the interior wall 21e (e.g.

cylindrical surface) inwardly (e.g. radially) towards the one or more straws 1. The distal free end of the protrusion(s) 24a, 24b may contact the exterior periphery and/or end(s) of the straw. The one or more pathways 25 may be defined between one or more adjacent protrusions 24a, 24b, and/or portions of the carrier/straw. The one or more protrusions 24a, 24b (e.g. radial) may be elongated. As shown in FIGS. 2-9A, the radial protrusions 24a, 24b, if used, may be elongated and extend for a length L along one or more lengths or portions of the body (e.g. interior wall) of the carrier 20, 120 to engage one or more lengths/portions of the straw exterior periphery. The elongated protrusion 24, 24a, 24b may extend beyond the length and/or one or more ends 1a of the straw, or may not extend past the extent or terminal end 1a of the straw. As shown in FIGS. 2-9A, the carrier 20, 120 and/or spline 24 may include an axial stop or stop mechanism 24c. The spline 24 or protrusion 24a, 24b (e.g. 24b on the fixed portion) may include the axial stop 24c radially projecting to engage/position/space the first end 1a and/or second end 1b of the straw from the first end 20a and/or inlet 22a. The axial stop 24c may extend for a distance D in the radial direction or along a radius to engage across the first end 1a and/or second end 1b, or portions thereof (e.g. one or more cylindrical ends defining the straw opening). Although not shown, the spline/protrusion 24a, 24b may not include the axial stop in some embodiments. The protrusions 24a, 24b, and/or 24c are shown as being in an annular pattern or annular/circumferentially spaced about the straw diameter/axis A and/or interior. It should be understood that the spline 24 and/or protrusions 24a, 24b (e.g. radial) may be of a variety of shapes, sizes, quantities, orientations, positions, and constructions and still be within the scope of the invention. For example, the elongated protrusions/splines (e.g. radial) may be in a nonlinear, spiral, or curve pattern about the longitudinal axis of the carrier/channel/straw in some embodiments rather than straight/axial in length as shown. Moreover, in some embodiments, the one or more protrusions may be curved, bumps, or domes in shape projecting from the one or more walls of the interior. Further, a plurality of protrusions may be aligned/patterned to form or define an elongated protrusion or offset extending for one or more lengths/circumferences. The protrusions 24a and/or splines 24 of the adjustable portion 26 may be tapered towards the outlet 22b and be tapered towards the inlet 22a as shown in FIGS. 2-9A. As shown in the one embodiment in FIGS. 2-9A, the protrusion 24b and/or splines 24 of the fixed portion 28 may be tapered towards the outlet 22b and be tapered towards the inlet 22a. Although not shown, the pin jet sprayer(s), if used, of the carrier may force the first fluid F1 through the interior periphery 1c and/or end 1a of the straw and/or exterior periphery 1d. The pin jet sprayer may be one or more nozzles to provide one or more spray patterns and/or flow rates. In some implementations, one or more straw carriers 20, 120, or portions thereof, may be adjustable to releasably engage/secure one or more straws 1 of a variety of diameters DD and/or lengths LL within the appliance, or portions thereof (e.g. rack, dishwasher tub). For example, a first straw 60 of a first diameter may be loaded/unloaded into the straw carrier 20, 120 in one application/wash cycle and a second straw of a second diameter, smaller than the first diameter, may be loaded/unloaded into the straw carrier 20, 120 in another application/wash cycle. This allows a single carrier/receptacle to secure one or more straws of different/same diameters DD. The length LL may be different/same and still be engaged by the collet straw carrier/receptacle receiving

different/same diameter straws. The straw carrier 20, 120 or one or more adjustable/movable portions 26 (e.g. sliding members, pivoting members, members) adjusts/reconfigures/positions (e.g. diameters, first radius, second radius, etc.) between at least one first position and at least one second position, different from the first position, to coincide with the corresponding variety of diameters DD of the one or more straws 1 to be washed/secured. The straw carrier 20, 120 may compress, squeeze, clamp, pin, or secure the straw 1 from the opposing ends 1a or 1b of the straw 1 in some embodiments. One or more spray elements 40 may be in fluid communication with the collet straw carrier 20, 120 and/or straw 1 (e.g. interior, exterior, ends, etc.). For example, when the carrier engages the ends 1a or 1b of the straw 1, this may leave a portion (e.g. exterior periphery 1d) between the opposing ends 1a, 1b of the straw 1 capable of being exposed to one or more fluid supplies (e.g. spray arm 42, apertures, spray elements 40). Although the collet/adjustable straw carrier 20, 120 is shown positioned in the dishwasher rack 30, the carrier 20, 120 may be in a variety of positions with the dishwasher tub 14 and/or appliance 10. Although the receptacle is shown for a single straw, the receptacle 22 may releasably engage a plurality of straws of a variety of lengths/diameters (e.g. straws in parallel) in some embodiments.

In some implementations, one or more collet straw carriers 20, 120, or portions thereof, with one or more straws 1 may be positioned downstream of one or more spray elements or apertures 40 and/or fluid supplies 16. The carrier(s) 20, 120 and/or straw(s) 1 may be positioned downstream of one or more spray elements 40 (e.g. the one or more apertures, fluid supply). For example, as shown in the one embodiment in FIG. 1, at least one spray arm 42, if used, may direct fluid F2 towards at least an exterior periphery 1d of the straw 1. In some embodiments, the spray arm 42 may direct fluid towards an interior periphery 1c, alone or along with the exterior periphery 1d. In the one embodiment shown in FIG. 1, the carrier 20, 120 (e.g. fixed portion) may engage, be adjacent to, and/or downstream of a docking station 41, aperture(s)/spray element 40, and/or fluid supply 16. The collet straw carrier 20, 120 (e.g. fixed portion) may have a spray collector 27a, if used, and/or nozzle, if used, (e.g. pin jet sprayer) in fluid communication with the spray element 40 and/or fluid supply 16.

As shown in FIGS. 1-9A, the carrier or collet straw carrier 20, 120, rack 30, and/or appliance 10 may include one or more members, components, or portions 26, 28. The one or more members/portions (e.g. 26, 28), or portions thereof, may define the one or more receptacles 22, or portions thereof, for receiving the straw 1 (e.g. at least one end 1a or 1b, portion of straw length LL). The one or more members of the collet straw carrier 20, 120 may include one or more adjustable members or portions 26 moveable/adjustable relative to one or more fixed members or portions 28 to vary a radial distance R and/or position (e.g. first radial position, second radial position, etc.) between one or more members. The adjustable portion 26 (e.g. member), or portions thereof, of the carrier 20, 120 may move (e.g. linearly, horizontally, vertically, radially, pivotably, slidably, angularly, etc.) between one or more positions (e.g. first, second, third, fourth, radial) relative to the fixed portion 28 to vary the radial distance R (e.g. increase, decrease) and/or position between one or more portions of the carrier (e.g. adjustable portion, fixed portion). By varying the distance or radius R between the fixed portion 28 and the adjustable portion 26, one or more straws 1 (e.g. opposing ends 1a or 1b) may be releasably engaged (e.g. compressed/engaged, uncom-

pressed/disengaged, radially engaged/disengaged) within the carrier 20, 120 and/or rack 30. As shown in FIGS. 1, 2, 5, 5A, 6, 9, and 9A, the adjustable portion 26 and/or the fixed portion 28 (e.g. receptacle 22) releasably engage at least one end of the straw 1. For example, the one or more adjustable portions 26 and/or receptacle 22 of the carrier(s) 20, 120 may releasably engage the first end 1a of the one or more straws 1 in one or more radial positions. The one or more fixed portion 28 and/or receptacle 22 of the carrier(s) 20, 120 may releasably engage the first end 1a of the one or more straws. The carrier 20, 120 may maintain the straw horizontally or angled relative to the horizontal in some embodiments. Although the straw 1 may be positioned substantially in a horizontal position as shown, the straw 1 may be orientated at an angle (e.g. 0 to 2) relative to the horizontal plane to assist in draining fluid from the straw (e.g. exterior periphery and/or interior periphery). For example, the carrier, or portions thereof, and/or the straw end 1a received in the receptacle 22 may be at a higher elevation than the other end 1b of the straw.

In some implementations, the collet straw carrier 20, 120 and/or appliance 10 may include the dishwasher rack 30. One or more of the collet straw carriers 20, 120 may be positioned in the rack 30 and in fluid communication with one or more spray elements 40.

In some implementations, the collet straw carrier 20, 120, rack 30, and/or dish washing appliance 10 may include one or more biasing mechanisms 50. One or more biasing mechanisms 50 may urge at least a portion of the one or more adjustable portions 26 or one or more members 26a (e.g. splines 24) towards or relative to (e.g. radially, inward) the one or more fix portions 28 (e.g. receptacle, axis), receptacle 22, straw 1 (e.g. end, exterior periphery), and/or remaining portions of the carrier 20, 120, or portions thereof. The one or more bias mechanisms 50 may urge the adjustable portion 26, or portions thereof, radially inward relative to the fixed portion 28 towards the exterior periphery 1d of the straw in the receptacle 22. The variety of positions (e.g. radial) of the adjustable portion(s) may vary the size and shape of the receptacle 22 and/or carrier 20, 120, or portions thereof. The larger the diameter DD of the straw 1, the more or larger force (e.g. spring force) is applied by the one or more biasing mechanisms 50 or portion(s) (e.g. member 26a, spline 24, 24a) of the adjustable portion 26 to the straw when in the secured or loaded position with the carrier 20, 120. The smaller the diameter DD of the straw 1, the less force (e.g. spring force) may be applied by the one or more biasing mechanisms 50 or portion(s) (e.g. member 26a, spline 24, 24a) of the adjustable portion 26 to the straw when in the secured or loaded position with the carrier 20, 120. Although the one or more biasing mechanisms 50 may be an elastic material as shown in the Figures, it should be understood that the biasing mechanism may be a variety of shapes, sizes, quantities, and constructions and still be within the scope of the invention. For example, one or more compression springs may be used. In the one embodiment shown in FIGS. 1-5A, the biasing mechanism 50 is an O-ring 51 (e.g. elastic material). In the one embodiment shown in FIGS. 6-9A, the biasing mechanism is an elastic sleeve 52. The one or more biasing mechanisms 50 may extend circumferentially (e.g. 360 degrees, less than 360 degrees, a plurality of spaced apart degrees) about the axis A of the receptacle 22 or straw 1, and/or the adjustable portion/member(s) 26, 26a. The bias mechanism may engage one or more adjustable portions 26 or members 26a as shown in the Figures. The biasing mechanism 50 may engage at least one of the adjustable portion and/or the fixed

11

portion when in one or more positions. The biasing mechanism **50** may engage one or more portions (e.g. lengths, members) of the adjustable portion **26** and/or first portion **28**. As shown in the FIGS. 1 and 6-9A, the biasing mechanism **50** (e.g. sleeve) extends substantially the length of the spline **24** (e.g. **24a**) or adjustable portion **26** (e.g. member **26a**) and/or a portion of the fixed portion **28**. As shown in FIGS. 1-5A, the O-ring **51** or biasing mechanism **50** engages one end of the adjustable portion **26** or member **26a** adjacent the fixed portion **28** (e.g. hinge, away from the outlet **22b**). It should be understood that the bias mechanism **50** may be of a variety of shapes, sizes, quantities, positions, and constructions and still be within the scope of the invention.

In some implementations, the collet straw carrier **20**, 120 may include one or more adjustable portions **26**, one or more fixed portions **28**, and/or one or more biasing mechanisms **50**. The adjustable member/portion **26** may be moveable or positionable between one or more positions relative to the fixed member/portion **28** to vary the radial position and/or radial distance **R** between the adjustable portion and the fixed/remaining portion. Varying the position (e.g. radial position(s)) of the adjustable portion **26** (e.g. one or more members **26a**) relative to the fixed portion **28** may releasably engage the straw **1** (e.g. at least one end). Varying the position of the adjustable portion **26** may vary (e.g. size, shape) the receptacle **22** (e.g. interior wall(s) of the carrier). The biasing mechanism **50**, if used, may position the adjustable portion **26** or members **26a** relative to the fixed portion **28** to vary the radial distance **R** and/or adjust to the diameter **DD** of the straw **1**. The straw **1**, positioned (e.g. stowed within, deployed from) relative to the carrier **20**, 120/receptacle **22**, may position the adjustable portion **26** relative to the fixed portion **28** to vary the radial distance **R** and/or adjust to the diameter **DD** of the straw **1**. The one or more adjustable portions **26** (e.g. members **26a**), or portions thereof, may releasably engage at least one end **1a** or **1b** of the one or more straws **1**. The adjustable portion **26** (e.g. member **26a**) may be configurable between at least one first position at a first radius **R1** (see FIGS. 3, 5, 7, and 9) and at least one second position at a second radius **R2** (see FIGS. 2, 5, 5A, 6, 9, and 9A). In some embodiments, the second radius **R2** may be larger than the first radius **R1**. Although not shown, in other embodiments, the first radius may be larger than the second radius. The biasing mechanism **50** may have a larger spring force when the adjustable portion **26**, or portions thereof, is in the second position at the larger second radius **R2** than the first position at the first radius **R1**. The biasing mechanism **50** may urge or move (e.g. pivotably, slidingly, linearly, arcuately) the adjustable portion **26** (e.g. member **26a**) radially inward from the second position/radius **R2** towards the first position/radius **R1**. Stowing the straw **1** or end **1a** into the carrier/receptacle/adjustable portion/fixed portion, pushes or urges the adjustable portion **26** (e.g. member **26a**) and/or bias mechanism **50** radially outward from the first position/radius **R1** to the second position/radius **R2**. This may increase the spring force of the bias mechanism **50**. When deployed the straw **1** or end **1a** from the carrier/receptacle/adjustable portion/fixed portion, the outward force applied by the inserted straw **1** is reduced/removed allowing the adjustable portion **26** (e.g. member **26a**) and/or bias mechanism **50** to move radially inward from the second position/radius **R2** to the first position/radius **R1**. This may decrease the spring force of the bias mechanism **50**. Moving the adjustable portion **26** (e.g. one or more members **26a**) from the second position/radius **R2** to the first position/radius **R1** narrows the receptacle **22** and moving the adjustable portion **26** (e.g. one or more members

12

26a) from the first position/radius **R1** to the second position/radius **R2** to broadens the receptacle **22**. It should be understood that different straws and/or straw diameters may correspond to different positions (e.g. radial) of the adjustable portion(s) **26** (e.g. members **26a**) relative to the fixed portion(s).

In some implementations, the collet straw carrier **20**, or portions thereof, may include one or more portions pivotably/hingedly connected to each other. The one or more 10 adjustable portions **26** may be pivotably connected to the one or more fixed portions **28** to vary the relative positions (e.g. radial). In the one embodiment shown in FIGS. 1-5A, one or more adjustable portions **26**/members **26a** is hingedly connected to the one or more fixed portions **28**. The adjustable portion(s) **26** or member(s) **26a** is hinged to the fixed portion(s) **28** between a variety of pivot angles to vary the radial distance **R** of the adjustable portion, or portions thereof. Although the pivoting member(s) **26a** may pivot at angles relative to the axis **A**, other directions/movement/ 15 orientations are contemplated. The adjustable portion **26** may pivot between the first position/radius **R1** (see FIG. 3) and the second position/radius **R2** (see FIG. 2). The hinge **60** may be connected between a second end **26d**, opposite a first end **26c**, of the adjustable portion(s)/member(s) **26a** and a first end **28a**, opposite a second end **28b**, of the fixed portion(s)/member(s) **28**. The first end **26c** of the adjustable portion(s) **26**/member(s) **26a** may define the funnel **29**, receptacle **22**, and/or outlet **22b**, or portions thereof. The second end **26d** of the adjustable portion(s) **26**/member(s) **26a** may define the hinge **60** and/or receptacle **22**, or portions thereof. The hinge portion **60** of the adjustable portion **26** may be one or more tabs **61**. Each hinged adjustable portion **26**/member **26a** may include at least one tab **61**. The hinge portion **60** of the fixed portion **28** may be one or more first circumferential grooves **62**. The first end **28a** of the fixed portion(s) **28** may define the receptacle **22** and/or the first circumferential groove **62**, or portions thereof. The second end **28b** of the fixed portion(s) **28** may define the receptacle **22** and/or inlet **22a**, or portions thereof. 20 Although the hinge **60** is shown as a tab **61** pivotably engaging the first circumferential groove **62**, a variety of hinges may be used and still be within the scope of the invention. The fixed portion **28** may be adjacent to or on the first end **20a** and/or inlet **22a** of the carrier **20** and the adjustable portion **26** may be adjacent to or on the second end **20b** and/or outlet **22b** of the carrier **20**. The biasing mechanism **50** may engage one or more portions of the collet straw carrier **20**. The biasing mechanism **50** (e.g. O-ring **51**) may engage or be positioned only on the adjustable portion **26** as shown FIGS. 2-5A. However, in some embodiments, the biasing mechanism **50** may engage the fixed portion or both the fixed portion and adjustable portion (see FIG. 7). The pivoting adjustable portion(s) **26** may include a second circumferential groove **26e** receiving the biasing mechanism **50** (e.g. O-Ring), or portions thereof. Each member **26a** may include a groove **26e**, or portion thereof. The groove **26e** may be substantially continuous in the first position/radius **R1** and/or discontinuous in the second position/radius **R2**. A plurality of pivoting members **26a** of the adjustable portion **26** may be pivotably connected to the hinged/fixed portion as shown, however it should be understood that at least two members **26a** of the adjustable portion **26** may be used in some embodiments. In some embodiments, a single pivoting member may be used. The plurality of pivoting members **26a** may splay open away from each other from the first position to the second position. The space between each adjustable member may be triangular in shape in at least the 25 30 35 40 45 50 55 60 65

second position and/or increases (e.g. angle increases) as the radius R increases from the axis A of the receptacle 22. In the second position/radius R2, the adjacent first ends 26c of the adjustable portions 26/pivoting members 26a are spaced further from each other than the adjacent second ends 26d of the adjustable portions 26/pivoting members 26a. The first end 26c/spline 24/protrusion 24a of the pivoting member(s) 26a may be positionable between the first position/radius R1 and the second position/radius R2. The second end 26d of the pivoting members 26a may be at the first radius R1 in both the first and second pivoting positions. The adjustable portion 26 or pivoting members 26a, or portions thereof, may include one or more splines 24a projecting radially inward towards the axis A of the receptacle 22 or straw 1. The splines 24a and/or interior wall 21e may define the one or more pathways 25 about the straw 1. As shown in FIGS. 1-5A, each pivoting member 26a of the adjustable portion 26 may include a spline 24a. The spline 24a, if used, may run for a length L in a direction from the outlet 22b towards the inlet 22a. The spline 24a may increase in height from the interior wall 21e of the adjustable portion then subsequently return or decrease in height to the interior wall 21e of the adjustable portion in a direction from the outlet 22b towards the inlet 22a. The fixed portion 28, or portions thereof, may include one or more splines 24b projecting radially inward towards the axis A of the receptacle 22 or straw 1. The splines 24b and/or interior wall 21e may define the one or more pathways 25 about the straw 1. The spline 24 (e.g. 24b), if used, may run for a length in a direction from the outlet 22b towards the inlet 22a. The spline/protrusion 24b may increase in height from the interior wall 21e of the adjustable portion then subsequently return or decrease in height to the interior wall 21e of the adjustable portion in a direction from the outlet 22b towards the inlet 22a. The spline/protrusion 24b and/or fixed portion 28 may include one or more axial stops 24c. The axial stop 24c of the spline(s) 24b may stop axial insertion or stowing of the end 1a of the straw 1. The adjustable portion 26 may be rotated about the axis A relative to the fixed portion 28.

In some implementations, the collet straw carrier 120, or portions thereof, may include one or more portions slidably connected to each other. The one or more adjustable portions 26 (e.g. members 26a) may be slidably connected to the one or more fixed portions 28 to vary the relative positions (e.g. radius). In the one embodiment shown in FIGS. 1 and 6-9A, one or more adjustable portions 26/members 26a (e.g. splines 24, protrusions 24a) is slidably connected to the one or more fixed portions 28. The adjustable portion(s) 26/members 26a is slidable relative to the fixed portion(s) 28 between a variety of radii/positions to vary the radial distance R of the adjustable portion 26/sliding members 26a, or portions thereof. The adjustable portion 26 (e.g. sliding members) may slide between the first position/radius R1 and the second position/radius R2. Although other directions are understood, the slidable member(s) 26a (e.g. spline) or adjustable portion 26 may slide perpendicular to the axis A of the receptacle 22 or straw 1 as shown. The adjustable portion 26 may include one or more slidable members 26a. The slidable members 26a may be or include splines 24/protrusions 24a. The slidable members 26a or adjustable portion 26 may include a variety of slidable engagements with the fixed portion 28. In the one embodiment shown in FIGS. 1 and 6-9A, the slidable engagement is a pin/member and slot engagement. The fixed portion 28 may include one or more slots 63. The slot(s) 63 may extend through the fixed portion 28 from the interior 21d to the exterior 21c. The slots 63 may be circumferentially spaced about the axis A. The

slots 63 may be elongated for a length between the first end 28a and the second end 28b of the fixed portion 28. The one or more slots 63 of the fixed portion 28 may slidably receive one or more slidable members 62a or one or more splines 24 of the adjustable portion 26. The slidable members 26a (e.g. splines 24) may slide within the slots 63 between the first position/radius R1 (see FIG. 7) and the second radius R2 (see FIG. 6). The slidable members 26a (e.g. outer end) may engage the biasing mechanism 50 surrounding the fixed/adjustable portions 28, 26 when at a sliding position beyond the diameter or outer extent of the exterior 21c of the fixed portion. The slidable members 26a (e.g. inner end) may extend radially inward from the inner extent of the interior 21d of the fixed portion to define one or more pathways 25. The larger the diameter of straw 1 the more the slidable members 26a or splines 24 are pushed radially outward. The length of the slidable member 26a and/or slot 63 may be positioned between the first end 28a of the fixed portion 28 and the second end 28b of the fixed portion. The length of the slidable member 26a and/or slot 63 may be elongated and extend for a length along the axis A of the receptacle or for a portion of the length of the carrier. The fixed portion 28, or portions thereof, may include one or more splines/protrusions 24, 24b projecting radially inward towards the axis A of the receptacle 22 or straw 1. The splines 24b and/or interior wall 21e may define the one or more pathways 25 about the straw 1. The spline 24b, if used, may run for a length in a direction from the inlet 22a towards the outlet 22b. The spline 24b may increase in height from the interior wall 21e of the adjustable portion then subsequently return or decrease in height to the interior wall 21e of the adjustable portion in a direction from the outlet 22b towards the inlet 22a. The protrusion 24b and/or fixed portion 28 may include one or more axial stops 24c. The axial stop 24c of the spline(s)/protrusions 24, 24b may stop axial insertion or stowing of the end 1a of the straw 1. The biasing mechanism 50 may surround both the fixed and adjustable portion. Each one of the slidable members may engage the biasing mechanism (e.g. sleeve) for a length along the axis A. The sleeve 52 may extend past the longitudinal extents of the sliding member 26a in some embodiments. The funnel 29 may be defined by the fixed portion 28.

Although one embodiment of the axial stop or stop mechanism 24c is shown in the Figures, it should be understood that the axial stop may be a variety of shapes, sizes, quantities, positions, and constructions and still be within the scope of the invention.

Although the adjustable portion 26 and/or members 26a may pivot or slide relative to the fixed portion 28 to releasably engage the straw 1 (e.g. outer diameter/periphery), it should be understood that the adjustable/fixed portion may be of a variety of shapes, sizes, quantities, movement, engagements, and constructions and still be within the scope of the invention.

In use, the user may deploy the dishwasher rack 30 to load one or more straws 1 when the one or more collet straw carriers 20, 120 is empty and need to be cleaned by the dish washing appliance 10. Alternatively, the one or more collet straw carriers 20, 120 may be inserted or coupled to the rack 30 if not already secured/fixed thereto. By increasing/decreasing or adjusting the radial distance R between the adjustable portion 26 (e.g. pivoting member(s), sliding member(s), spline 24) and the fixed portion 28 may allow one or more straws 1 to be loaded and/or unloaded from the collet straw carrier 20, 120. As shown in the embodiment in FIGS. 1, 2, 5, 5A, and 6, the user may engage one end 1a of the straw 1 to the second end 20b, outlet 22b, receptacle 22,

fixed portion 28, and/or adjustable portion 26. The user and/or straw 1 may then be used to actuate or move (e.g. slide, pivot) the adjustable portion 26 or members 26a (e.g. sliding, pivoting) relative to the fixed portion 28 to position the adjustable portion 26 away (e.g. radially) from the fixed portion 28. Thereby the biasing mechanism 50, if used, may be stretched/biased when increasing the radial distance R of the one or more members 26a or adjustable portion 26. The biasing mechanism 50 urges the adjustable portion(s)/members 26, 26a against/towards the straw 1, thereby pinning the straw against another adjustable member/portion and/or fixed portion. Varying the radial distance R between the adjustable portion 26 and the fixed portion 28 releasably engages the end 1a of the one or more straws 1 of a variety of diameters DD. Once the one or more straws 1 are loaded in the collet straw carrier 20, 120, the rack 30 may be stowed within the dishwasher tub 14. When stowed, one or more portions of the carrier 20 may engage, fluidly couple, or be in fluid communication with one or more spray elements 40. For example, a spray element 40 (e.g. docking station) may spray fluid in the fixed portion, one or more ends of the straw, and/or through the nozzle (e.g. pin jet sprayer), if used, into or towards a straw. In some embodiments, a spray element 40 (e.g. one or more spray arms) may be used to direct fluid towards one or more portions of the straw 1 (e.g. exterior periphery). As shown in the Figures, the spray arm 42 and/or the docking station 41 may spray or direct fluid towards one or more portions of the straw. Once the one or more washing cycles are completed, the user may deploy the rack 30, if used, and unload the one or more straws 1. The biasing mechanism 50, if used, may return itself, the adjustable portion 26, or portions thereof, to a rest or another position (e.g. smaller radial distance). Although a straw of a variety of diameters DD is shown engaged with the carrier 20, 120, it should be understood that the straw or other washable items may be a variety of shapes, sizes, quantities, and constructions may still be within the scope of the invention. For example, the straw may include an angle along its length. The carrier may engage one or more straws of a variety of lengths LL. Further, for example, the carrier may releasably engage washable items having exteriors other than circular. Further, washable items may not be hollow in some embodiments. For example, square, rectangular in cross section and/or solid cores. Other washable items may include, but is not limited to, appliance parts, baby items, etc.

It should be understood that the collet straw carrier may be a variety of shapes, sizes, quantities, and construction and still be within the scope of the invention. For example, the carrier/receptacle may releasably hold and wash two straws of different diameters in some embodiments.

While several embodiments have been described and illustrated herein, those of ordinary skill in the art will readily envision a variety of other means and/or structures for performing the function and/or obtaining the results and/or one or more of the advantages described herein, and each of such variations and/or modifications is deemed to be within the scope of the embodiments described herein. More generally, those skilled in the art will readily appreciate that all parameters, dimensions, materials, and configurations described herein are meant to be exemplary and that the actual parameters, dimensions, materials, and/or configurations will depend upon the specific application or applications for which the teachings is/are used. Those skilled in the art will recognize, or be able to ascertain using no more than routine experimentation, many equivalents to the specific embodiments described herein. It is, therefore, to be under-

stood that the foregoing embodiments are presented by way of example only and that, within the scope of the appended claims and equivalents thereto, embodiments may be practiced otherwise than as specifically described and claimed. 5 Embodiments of the present disclosure are directed to each individual feature, system, article, material, and/or method described herein. In addition, any combination of two or more such features, systems, articles, materials, and/or methods, if such features, systems, articles, materials, and/or methods are not mutually inconsistent, is included within the 10 scope of the present disclosure.

All definitions, as defined and used herein, should be understood to control over dictionary definitions, definitions in documents incorporated by reference, and/or ordinary 15 meanings of the defined terms.

The indefinite articles "a" and "an," as used herein in the specification and in the claims, unless clearly indicated to the contrary, should be understood to mean "at least one."

The phrase "and/or," as used herein in the specification 20 and in the claims, should be understood to mean "either or both" of the elements so conjoined, i.e., elements that are conjunctively present in some cases and disjunctively present in other cases. Multiple elements listed with "and/or" should be construed in the same fashion, i.e., "one or more" 25 of the elements so conjoined. Other elements may optionally be present other than the elements specifically identified by the "and/or" clause, whether related or unrelated to those elements specifically identified. Thus, as a non-limiting example, a reference to "A and/or B", when used in conjunction with open-ended language such as "comprising" 30 can refer, in one embodiment, to A only (optionally including elements other than B); in another embodiment, to B only (optionally including elements other than A); in yet another embodiment, to both A and B (optionally including other elements); etc.

As used herein in the specification and in the claims, "or" 35 should be understood to have the same meaning as "and/or" as defined above. For example, when separating items in a list, "or" or "and/or" shall be interpreted as being inclusive, i.e., the inclusion of at least one, but also including more than one, of a number or list of elements, and, optionally, additional unlisted items. Only terms clearly indicated to the contrary, such as "only one of" or "exactly one of," or, when 40 used in the claims, "consisting of," will refer to the inclusion of exactly one element of a number or list of elements. In general, the term "or" as used herein shall only be interpreted as indicating exclusive alternatives (i.e. "one or the other but not both") when preceded by terms of exclusivity, such as "either," "one of," "only one of," or "exactly one of." 45 "Consisting essentially of," when used in the claims, shall have its ordinary meaning as used in the field of patent law.

As used herein in the specification and in the claims, the phrase "at least one," in reference to a list of one or more elements, should be understood to mean at least one element 50 selected from any one or more of the elements in the list of elements, but not necessarily including at least one of each and every element specifically listed within the list of elements and not excluding any combinations of elements in the list of elements. This definition also allows that elements 55 may optionally be present other than the elements specifically identified within the list of elements to which the phrase "at least one" refers, whether related or unrelated to those elements specifically identified. Thus, as a non-limiting example, "at least one of A and B" (or, equivalently, "at least one of A or B," or, equivalently "at least one of A and/or B") can refer, in one embodiment, to at least one, optionally including more than one, A, with no B present (and option-

17

ally including elements other than B); in another embodiment, to at least one, optionally including more than one, B, with no A present (and optionally including elements other than A); in yet another embodiment, to at least one, optionally including more than one, A, and at least one, optionally including more than one, B (and optionally including other elements); etc.

It should also be understood that, unless clearly indicated to the contrary, in any methods claimed herein that include more than one step or act, the order of the steps or acts of the method is not necessarily limited to the order in which the steps or acts of the method are recited.

In the claims, as well as in the specification above, all transitional phrases such as "comprising," "including," "carrying," "having," "containing," "involving," "holding," "composed of," and the like are to be understood to be open-ended, i.e., to mean including but not limited to. Only the transitional phrases "consisting of" and "consisting essentially of" shall be closed or semi-closed transitional phrases, respectively, as set forth in the United States Patent Office Manual of Patent Examining Procedures, Section 2111.03.

It is to be understood that the embodiments are not limited in its application to the details of construction and the arrangement of components set forth in the description or illustrated in the drawings. The invention is capable of other embodiments and of being practiced or of being carried out in various ways. Unless limited otherwise, the terms "connected," "coupled," "in communication with," and "mounted," and variations thereof herein are used broadly and encompass direct and indirect connections, couplings, and mountings. In addition, the terms "connected" and "coupled" and variations thereof are not restricted to physical or mechanical connections or couplings.

The foregoing description of several embodiments of the invention has been presented for purposes of illustration. It is not intended to be exhaustive or to limit the invention to the precise steps and/or forms disclosed, and obviously many modifications and variations are possible in light of the above teaching.

The invention claimed is:

1. A collet straw carrier for a dish washing appliance comprising:

a fixed portion and an adjustable portion defining a receptacle configured to receive an end of a straw; one or more biasing mechanisms, wherein the one or more biasing mechanisms urges the adjustable portion relative to the fixed portion to releasably engage an end of a straw within the receptacle; and wherein the adjustable portion is hingedly connected to the fixed portion.

2. The collet straw carrier of claim 1 wherein the one or more biasing mechanisms urge the adjustable portion radially inward relative to the fixed portion towards an end of a straw in the receptacle.

3. The collet straw carrier of claim 1 further comprising an axial stop within the receptacle.

4. The collet straw carrier of claim 1 wherein the adjustable portion is configurable between a first position at a first radius and a second position at a second radius larger than the first radius.

5. The collet straw carrier of claim 4 wherein the one or more biasing mechanisms have a larger spring force when the adjustable portion is in the second position than the first position.

18

6. The collet straw carrier of claim 1 includes a first end and an opposing second end, and the adjustable portion is on the second end and the fixed portion is on the first end.

7. The collet straw carrier of claim 1 wherein the adjustable portion includes two or more pivoting members hingedly connected to the fixed portion.

8. The collet straw carrier of claim 1 wherein the adjustable portion includes a circumferential groove receiving the one or more biasing mechanisms.

9. The collet straw carrier of claim 1 wherein the adjustable portion is slidably connected to the fixed portion.

10. The collet straw carrier of claim 9 wherein the fixed portion includes one or more slots slidably receiving one or more sliding members of the adjustable portion.

11. The collet straw carrier of claim 10 wherein the one or more sliding members slide perpendicular to an axis of the receptacle.

12. The collet straw carrier of claim 9 wherein the one or more sliding members and/or one or more slots are elongated and extend for a length along an axis of the receptacle.

13. The collet straw carrier of claim 1 wherein the one or more bias mechanisms extend circumferentially about an axis of the receptacle.

14. The collet straw carrier of claim 1 further comprising a funnel defining an inlet of the receptacle.

15. A dish washing appliance comprising:

a dishwasher tub;

one or more spray elements disposed in the dishwasher tub, wherein the one or more spray elements is in fluid communication with a fluid supply to direct fluid from the fluid supply into the dishwasher tub;

one or more collet straw carriers positioned downstream of the one or more spray elements, wherein the carrier includes a fixed portion, an adjustable portion, and one or more biasing mechanisms, wherein the fixed portion and the adjustable portion define a receptacle configured to receive an end of a straw, and wherein the one or more biasing mechanisms urges the adjustable portion relative to the fixed portion to releasably engage an end of a straw within the receptacle; and

wherein the adjustable portion is hingedly connected to the fixed portion.

16. The dish washing appliance of claim 15 wherein the adjustable portion is slidably connected to the fixed portion.

17. The dish washing appliance of claim 15 wherein the bias mechanism extends circumferentially about an axis of the receptacle.

18. The dish washing appliance of claim 15 further comprising a funnel defining an inlet of the receptacle.

19. The dish washing appliance of claim 15 wherein the one or more biasing mechanisms urges the adjustable portion radially inward relative to the fixed portion towards an end of a straw in the receptacle.

20. The dish washing appliance of claim 15 further comprising an axial stop within the receptacle.

21. The dish washing appliance of claim 15 wherein the adjustable portion is configurable between a first position at a first radius and a second position at a second radius larger than the first radius.

22. The dish washing appliance of claim 21 wherein the one or more biasing mechanisms have a larger spring force when the adjustable portion is in the second position than the first position.

23. A method of releasably engaging one or more straws with a collet straw carrier within a dish washing appliance comprising the steps of:

providing at least one collet straw carrier within a dish-washer tub, wherein the carrier includes one or more fixed portions and one or more adjustable portions, and wherein the one or more adjustable portions move relative to the one or more fixed portions;

varying a radial position of the one or more adjustable portions relative to the one or more fixed portions; 10

releasably engaging an end of a straw; and

pivotting the one or more adjustable portions relative to the one or more fixed portions.

24. The method of claim **23** further comprising sliding the one or more adjustable portions relative to the one or more fixed portions. 15

25. The method of claim **23** further comprising biasing the one or more adjustable portions relative to the one or more fixed portions.
